(57) **CLAIM**

The ornamental design for a click lock corner, as shown and described.

DESCRIPTION

FIG. 1 is left, side perspective view of a click lock corner, showing our new design;

FIG. 2 is a right, side perspective view thereof;

FIG. 3 is an upper, left perspective view thereof;

FIG. 4 is an upper, right perspective view thereof;

FIG. 5 is a lower, left perspective view thereof;

FIG. 6 is a lower, right side perspective view thereof;

FIG. 7 is an upper, front perspective view thereof;

FIG. 8 is a lower, front perspective view thereof;

FIG. 9 is a rear, right perspective view thereof;

FIG. 10 is a rear, left perspective view thereof;

FIG. 11 is a front view thereof;

FIG. 12 is a rear view thereof;

FIG. 13 is a left, side view thereof;

FIG. 14 is a right, side view thereof;

FIG. 15 is a left, corner view thereof;

FIG. 16 is a right, corner view thereof;

FIG. 17 is a top view thereof; and,

FIG. 18 is a bottom view thereof.
